203,987

MASS CORE MEMORY ENCLOSURE FOR ELECTRONIC DATA PROCESSING

Ronald E. Loosen, Woodland Hills, and Leon C. Sanderson, Los Angeles, Calif., assignors to Ampex Corporation, Redwood City, Calif., a corporation of California

Filed Nov. 9, 1964, Ser. No. 82,523

Term of patent 14 years

(Cl. D26—5)

FIG. 1

FIG. 2

FIGURE 1 is a front and right side perspective of a mass core memory enclosure for electronic data processing, showing our new design;

FIGURE 2 is a right side elevation;

FIGURE 3 is a back elevation;

FIGURE 4 is a plan;

FIGURE 5 is a left side elevation; and

FIGURE 6 is a broken-away front and right side perspective view of the portion enclosed by arrows 6-6 in FIGURE 1.

We claim:

The ornamental design for a mass core memory enclosure for electronic data processing, substantially as shown and described.

References Cited by the Examiner

Data Processing Equipment Encyclopedia, volume 2, Monthly updating, April 1963, Electronic Equipment, page 4, DDP-24 core memory by Computer Control Co., Inc.

EDWIN H. HUNTER, Primary Examiner.

WILLIAM M. HENRY, Assistant Examiner.